UNITED STATES PATENT OFFICE.

FREDERICK CATLIN, OF NEW YORK, N. Y., ASSIGNOR TO MAX LOEWENSTEIN, OF SAME PLACE.

FUNNEL.

SPECIFICATION forming part of Letters Patent No. 334,564, dated January 19, 1886.

Application filed April 13, 1885. Serial No. 162,072. (No model.)

To all whom it may concern:

Be it known that I, FRED. CATLIN, of the city, county, and State of New York, have invented a new and Improved Funnel, of which the following is a full, clear, and exact description.

The object of my invention is to provide a new and improved funnel, to be used not only for pouring liquid from one vessel into another, but also for measuring and conveying or transporting liquids.

The invention consists in the construction and arrangement of parts, as will be herein-after fully described and claimed.

Reference is to be had to the accompanying drawing, forming part of this specification, in which the figure is a sectional elevation of my improved filter.

A neck, A², formed at the lower end of the funnel A, is screwed into a cock-casing, E, containing a plug, E'. In the lower end of the cock-casing an outlet-tube, F, is screwed and is surrounded by a flat ring, F', screwed on the lower end of the cock-casing. Air-vent apertures G are formed in the lower part of a cock-casing.

When the funnel is being used, the plate or flat ring F' rests on the top of the bottle, the tube F projecting down into the said bottle, the cock E is opened, and the liquid poured into the funnel passes down through the same and through the tube F into the bottle.

If it is desired to transport the liquid, the

cock E is closed before the funnel is filled, and if the liquid is to be drawn it is only necessary to open the cock-casing. The flow of liquid from the funnel can be stopped at any time by closing the cock E.

Having thus fully described my invention, I claim as new and desire to secure by Letters Patent—

1. The combination, with a funnel, of the longitudinally and horizontally apertured cock-casing E on the lower end of the same, having a cock, E', in said horizontal aperture, and the vent-apertures G, the tube F, secured in the lower end of the cock-casing and forming a continuation of the longitudinal aperture thereof, and the plate F, secured to the lower end of the cock-casing, and having a central aperture through which the tube passes, said aperture being of greater diameter than the tube, the inner ends of the vent-apertures G communicating with the space formed between said plate and tube, substantially as set forth. 55

2. In a funnel, the cock-casing E, formed with the longitudinal and transverse apertures, two concentric screw-threaded sockets in its under face, vent-apertures G, leading from the space between said sockets to the outer face of the casing, an upper screw-thread, and a cock, E', substantially as set forth. 60

FREDERICK CATLIN.
